UNITED STATES PATENT OFFICE.

OLUF TYBERG, OF NEW YORK, N. Y., ASSIGNOR TO RUFUS L. PATTERSON AND GEORGE ARENTS, JR., OF NEW YORK, N. Y.

CUTTING MECHANISM.

SPECIFICATION forming part of Letters Patent No. 782,981, dated February 21, 1905.

Application filed August 1, 1901. Renewed June 24, 1904. Serial No. 213,958.

To all whom it may concern:

Be it known that I, OLUF TYBERG, a citizen of the United States, residing at New York, county of Kings, and State of New York, have invented certain new and useful Improvements in Cutting Mechanisms, fully described and represented in the following specification and the accompanying drawings, forming a part of the same.

10 This invention relates to certain improvements in cutting mechanism.

In cutting mechanisms for cutting sheet material—such, for instance, as leaves of tobacco—it is usual to provide a cutting-bed on which the leaf is held by suction, said bed supporting a cutting-die which comprises two sections. A cutting-roller is provided which coöperates with said die and reciprocates there-over. To keep the edge of the die in good cutting order, it is necessary to frequently sharpen it; but it has been found that it is practically impossible to grind the two sides or sections of the die in such a way as to keep their cutting edges in the same horizontal plane. If, however, one side of the die is lower than the other, the roller does not produce a clean cut, as it reciprocates over the die if it coacts with both sides or sections at the same time. For this reason, therefore, it has been customary to arrange the cutting-roller so that it coöperates with one section of the die during one stroke of the reciprocation and with the other section of the die during the other stroke of the reciprocation, the roller being given a rocking movement in the direction of its axis between the strokes. In the construction referred to the roller has heretofore been in the form of a cylinder. When, therefore, it is rocked in the direction of the axis, as before described, it happens that during the cutting operation it stands at an angle which is slightly acute to the cutting edge with which it coöperates.

The present invention has for its object to produce a cutting mechanism which shall be generally of the class hereinbefore referred to, but in which the cutting device which coöperates with the die shall be so constructed

that it will stand at a right angle to the edge of the die during the cutting operation. 50

With this and other objects in view the invention consists in certain constructions and in certain parts, improvements, and combinations, as will be hereinafter fully described and then specifically pointed out in the claims 55 hereunto appended.

In the accompanying drawings, which form a part of this specification, and in which like characters of reference indicate the same parts, Figure 1 is a plan view of a cutting mechanism constructed in accordance with the invention. Fig. 2 is a side view of the construction illustrated in Fig. 1. Figs. 3 and 4 are diagrammatic views illustrating the position of the coöperating cutting-roller on each 65 stroke of the reciprocating movement.

The cutting mechanism which forms the subject of the present invention is intended to be used in connection with an organized machine for making cigars or cheroots—such, 70 for instance, as that described in United States Letters Patent to Oluf Tyberg, No. 654,203, dated July 24, 1900—and is intended to be operated by one of the moving parts of said machine. Inasmuch, however, as it is capable of 75 use in other machines and for cutting material other than tobacco-leaves, and inasmuch as the cutting mechanism proper has no special relation to the rest of said machine, it has been deemed unnecessary to illustrate any of the 80 parts of said machine or the particular moving parts from which the cutting mechanism is operated, it being understood that the parts of the cutting mechanism may be driven from any suitable source of power. 85

Referring to the drawings, 1 indicates a cutting-bed which serves to support a cutting-knife, said knife comprising two cutting-sections 2 and 3. The cutting-bed will preferably be a suction-bed and is therefore illustrated as provided with the usual perforations 4, through which the suction operates to hold the material to be cut on the bed, the suction required being obtained from any suitable source and operating through the pipes 5, 6, 90 and 7. The construction by which the suc-

tion is obtained and the construction of the cutting-bed itself may be similar to that disclosed in the patent above referred to, and reference is accordingly made to said patent 5 for a full disclosure of said constructions. The coöperating cutting device, which coacts with the knife and forces the material to be cut thereagainst, may be of any suitable construction. It comprises, however, two parts, 10 which are so arranged with relation to each other and the knife that during the cutting operation that one of the parts which is coöperating with one of the sections of the cutting edge will stand at a right angle thereto. 15 In the specific form of the construction illustrated the cutting device consists of a cutting roller 8, said roller consisting of the frusta of two cones placed base to base, and therefore being double-cone-shaped, one of the cone-shaped parts, *a*, being arranged to coöperate with one of the sections of the knife, and the other cone-shaped part, *b*, being arranged to coöperate with the other section of the knife. The roller is carried in an arm 9, said arm being 20 mounted on a carriage 10, which reciprocates on ways 11, the reciprocation of the carriage being produced in any suitable manner, as by a lever 12, which is connected by a link 13 to a stud 14 on the carriage, the lever 12 being 25 actuated by any suitable source of power. The arm 9 is or may be provided with a projection 30 15, which bears against a spring-operated plug 16, the spring which operates the plug being maintained in a suitable cup 17, mounted on 35 the carriage. It may be here remarked that the construction of the carriage and the parts for operating it is or may be substantially similar to that shown in the patent above referred to. The roller is arranged, as has been 40 before stated, so that one of its cones coöperates with and its surface is at right angles to one of the cutting-sections of the knife during one stroke of the reciprocation of the carriage and the other cone coöperates with the other 45 section of the knife and its surface is at right angles thereto during the other stroke of the reciprocation of the carriage. While the positioning of the roller may be effected in various ways, the construction preferably employed will be that shown in the patent above 50 referred to. Inasmuch as the construction is fully set forth in the patent, it is deemed unnecessary to describe it here further than to say that the arm 9 is carried on a lever 18, 55 which is suitably journaled in the carriage 10, said lever having its lower end in engagement with a shifting cam-plate 19, which contacts with suitable stops 20 and 21 at the end of each stroke of the reciprocation. The position 60 of the roller during each stroke of the reciprocation is well shown in Figs. 3 and 4. In Fig. 3 the cone *b* of the roller is coöperating with the section 3 of the cutting edge of the knife, and it will be seen that the surface of

the cone *b* is substantially at right angles to 65 this section. In Fig. 4, the cone *a* is shown as coöperating with the section 2 of the cutting edge of the knife, the roller having in the meantime completed one stroke of the reciprocation and having had its position shifted 70 by the mechanism before described. As illustrated in Fig. 4, it will be seen that the surface of the cone *a* is substantially at right angles to the edge of the cutting-section 2.

While the construction which has been described illustrates a preferred form of the invention, it is to be understood that the invention is not to be limited thereto, as it may be embodied in other forms of construction. 75

What is claimed is—

1. In a cutting mechanism, the combination with a die having a cutting edge including two cutting-sections, of a cutting device having two parts, means for producing a reciprocating movement between the cutting device and the die, and means for varying the relative position of the die and the device so that one part of the device coöperates with one section of the cutting edge of the die and is at right angles thereto during one stroke of the reciprocation and the other part coöperates with the other section of the cutting edge of the die and is at right angles thereto during the other stroke of the reciprocation, substantially as described. 90

2. In a cutting mechanism, the combination with a die having a cutting edge including two cutting-sections, of a cutting device having two angularly-disposed parts, means for producing a reciprocating movement between the cutting device and the die, and means for varying the relative position of the die and the device so that one part of the device coöperates with one section of the cutting edge of the die and is at right angles thereto during one stroke of the reciprocation and the other part coöperates with the other section of the cutting edge of the die and is at right angles thereto during the other stroke of the reciprocation, substantially as described. 100

3. In a cutting mechanism, the combination with a die having a cutting edge including two cutting-sections, of a cutting device having two angularly-disposed parts, means for reciprocating the cutting device over the die, and means for varying the relative position of the die and the device so that one part of the device coöperates with one section of the cutting edge of the die and is at right angles thereto during one stroke of the reciprocation and the other part coöperates with the other section of the cutting edge of the die and is at right angles thereto during the other stroke of the reciprocation, substantially as described. 115

4. In a cutting mechanism, the combination with a die having a cutting edge including two cutting-sections, of a cutting device having

two angularly-disposed parts, means for producing a reciprocating movement between the cutting device and the die, and means for changing the position of the device with respect to the die, so that one part of the device coöperates with one section of the cutting edge of the die and is at right angles thereto during one stroke of the reciprocation and the other part coöperates with the other section of the cutting edge of the die and is at right angles thereto during the other stroke of the reciprocation, substantially as described.

5. In a cutting mechanism, the combination with a die having a cutting edge including two cutting-sections, of a double-cone-shaped cutting-roller, means for producing a reciprocating movement between the roller and the die, and means for varying the relative position between the roller and the die, so that one part 15 of said roller coöperates with one section of the cutting edge of the die and its surface is at right angles thereto during one stroke of the reciprocation and the other part coöperates with the other section of the cutting edge of 20 the die and its surface is at right angles thereto during the other stroke of the reciprocation, substantially as described.

6. In a cutting mechanism, the combination with a die having a cutting edge including two cutting-sections, of a double-cone-shaped cutting-roller, means for reciprocating the roller over the die, and means for varying the relative position between the roller and the die, so that one part of said roller coöperates with one section of the cutting edge of the die and its surface is at right angles thereto during one stroke of the reciprocation and the other part coöperates with the other section of the cutting edge of the die and its surface is at 35 right angles thereto during the other stroke of the reciprocation, substantially as described.

right angles thereto during the other stroke of the reciprocation, substantially as described.

7. In a cutting mechanism, the combination with a die having a cutting edge including two cutting-sections, of a double-cone-shaped cutting-roller, means for producing a reciprocating movement between the roller and the die, and means for giving the roller a rocking movement in the direction of its axis so that one of its parts coöperates with one section of the cutting edge of the die and its surface is at 40 right angles thereto during one stroke of the reciprocation and the other part coöperates with the other section of the cutting edge of the die and its surface is at right angles thereto during the other stroke of the reciprocation, 45 substantially as described.

8. In a cutting mechanism, the combination with a die having a cutting edge including two cutting-sections, of a double-cone-shaped cutting-roller, means for reciprocating the roller over the die, and means for giving the roller a rocking movement in the direction of its axis so that one part of said roller coöperates with one section of the cutting edge of the die and its surface is at right angles thereto during 50 one stroke of the reciprocation and the other part of the roller coöperates with the other section of the cutting edge of the die and its surface is at right angles thereto during the other stroke of the reciprocation, substantially 55 as described.

In testimony whereof I have hereunto set my hand in the presence of two subscribing witnesses.

OLUF TYBERG.
